CLAIM

The ornamental design for a container for disseminating insecticidal or other vapors, as shown and described.

DESCRIPTION

FIG. 1 is a top perspective view of a container for disseminating insecticidal or other vapors embodying my new design, with the container being in an open position;

FIG. 2 is a bottom perspective view thereof, with the container in its closed position;

FIG. 3 is a top plan view thereof;

FIG. 4 is a side elevational view of FIG. 1;

FIG. 5 is an end elevational view of FIG. 1, and

FIG. 6 is a bottom plan view thereof.
